SHOCKLESS HAMMER

Herbert L. Ivins, Brooklyn, Ohio, assignor to Olin Mathie-
son Chemical Corporation, East Alton, Ill., a corpora-
tion of Virginia

Application July 8, 1958, Serial No. 747,229

9 Claims. (Cl. 145—29)

This invention relates to a striking tool or implement for fastener driving and more particularly to a masonry type hammer having a novel construction for manually driving a pointed pin or stud into steel, concrete or the like with a minimum number of hard blows and with the least shock to the hand of the person using the hammer.

Nail, sledge and masonry hammers with a solid head rigidly attached to a handle are well known, but where such heretofore known hammers are used, it is a common experience that the shock and vibration to the operator are very tiring and uncomfortable. This is especially so where the hammer is employed to drive fasteners into highly resistant materials such as masonry and steel. In recognition of this difficulty, hammers have been devised with springs, with separate movable bodies such as shot or a slug in the head, or with elastically cushioned handles in an effort to improve their ease of operation. These prior devices have not been altogether satisfactory because of accompanying serious disadvantages. Some have a disagreeably multiplied rebound and are subject to frequent breakdown which are more annoying than the type of shock which they reduce. Some fail to deliver a sufficient proportion of the driving energy and, thus, prolong the work. Still others are very difficult on the working hand of the operator and tend to develop painful blisters and calluses.

Therefore, an object of this invention is to provide an improvement in hammers which is characterized both by effective performance as well as ease of operation.

Another object is to provide a hammer characterized by the least rebound and shock transmission.

Another object is to provide a simple hammer structure including an elastic medium of a special type and in a special position so arranged as to not only dissipate the restitutinal energy effectively, but to also have substantially no wear and breakage.

Another object is to provide an economical hammer construction characterized by practical elimination of the bounce while being at the same time capable of delivering a blow of maximum energy.

These and other objects which will become apparent from a description of an embodiment of this invention are achieved by providing a special hammer head fitted with a confined but movable elastic member, and a suitable handle. More specifically elastic O-rings and receiving grooves are employed in the head. Just how the objects of this invention are accomplished will be better understood from the description of the preferred embodiment shown in the drawing wherein:

Fig. 1 is a side elevational view of this embodiment shown partly in cross section;

Fig. 2 is a fragmentary view showing the top of the hammer head of Figure 1;

Fig. 3 is an enlarged fragmentary cross section showing the action at an O-ring in the device of Figure 1 during impact;

Fig. 4 is a graphic representation of the comparative

2

performance characteristics of the device of this invention; and

Fig. 5 is a cross section through the handle grip taken on line V—V of Figure 1.

5 In accordance with this invention, a striking device such as a hammer or punch is provided which consists of separated telescoped parts having complementary recesses at which the parts are maintained in operatively connected relationship by intervening deformable means 10 of recoverable shape allowing only limited relative movement of the parts, one of which is the striker and the other a restitutinal counter weight. The arrangement is of such a nature because of the masses and elasticity as to eliminate rebound for all practical purposes or at least 15 to reduce it so greatly as to eliminate perceptible bounce of the ram or hammer head. Elastomeric inserts constrained between the recesses are contemplated as connectives. A driving force is applicable in any suitable manner from the counteracting member to the head but for 20 manual operation a handle is preferred. This is connected to the assembled striker and weight which take the form of a cylinder and surrounding barrel together constituting a head. For a hand-tool the handle is further provided with an elastic hand grip, preferable an oval 25 sectioned rubber grip mounted on the opposite end of the handle, preferably a round hollow handle, with the major dimension of the grip aligned parallel with the striking axis of the head. This arrangement adds the least rebound rigidity to the hammer handle and gives the maximum of a super-added shock absorption in the handle to further dampen even the small fraction of residue of restitutinal energy not put to good use by means of the aforementioned special head construction.

As shown in Figures 1 and 2, the hammer head includes 30 a tubular barrel 1 of steel of desired mass and dimensions. For driving fasteners such as pins and studs with penetrating shanks of a diameter of about $\frac{3}{16}$ of an inch more or less into concrete and steel, the barrel is a tube about 2 $\frac{1}{2}$ inches long and about 1 $\frac{1}{2}$ inches outer diameter and 35 about 1 $\frac{3}{16}$ inches inside diameter leaving a wall of desired weight. The head also includes a solid striker cylinder 2 of steel received in the bore of the barrel and having an impact head 3 at one end protruding out of the barrel and preferably of enlarged diameter. This mating striker has 40 a diameter of 1 $\frac{1}{16}$ of an inch in the cylindrical shank in the barrel and has a 1 $\frac{1}{2}$ inch diameter head of $\frac{3}{4}$ inch length included in the overall length of 4 $\frac{1}{2}$ inches of the striker. Each of these two parts are recessed at four V-grooves 4 and 5 spaced at intervals of $\frac{1}{2}$ of an inch to a 45 depth of about $\frac{1}{32}$ of an inch.

The barrel consists of a suitable material such as S.A.E. 1020—1030 steel not heat treated, while the striker is a tough hard material such as S.A.E. 1045—1050 steel heat treated to a Rockwell hardness of Rc45—50.

50 The restrained elastic connective inserts 10, 11, 12 and 13 are shaped so as to be not only deformable under compression with concomitant lateral distension, but also readily rolled even when deformed. Balls or rings of any 55 suitable elastomer such as ordinary rubber, neoprene, silicone rubber, or polyfluoroethylene are contemplated, provided equivalent to rubber having a Durometer hardness of approximately 70 preferably. At least two sets of axially displaced elastic members are desired so as to 60 maintain axial alignment of barrel and striker. The least number are preferred for ease of assembly. The greater the number of rings the heavier the duty which the hammer can withstand, but the greater is the force needed to press striker 2 into head 1 with the rings between them. 65 Four rings were found preferable for the hand-tool for the load conditions contemplated.

The receiving recesses for the insert are complementary

ball pockets or annular grooves such as the four grooves 4 in the barrel 1 and grooves 5 in striker 2 for the rings.

The sides of the recess are angularly sloped to avoid the total restraint of semi-circular or U-shaped grooves while providing limited desired action and reaction force dissipating deformation and movement. These sides are shown in the enlarged view of Figure 3 to be tangential at an included angle of 120° to the $\frac{1}{8}$ inch diameter arcuate bottom of the grooves. The spacing between parts 1 and 2 in the barrel bore is about $\frac{1}{16}$ of an inch for reception of O-rings having a torus diameter of $\frac{1}{8}$ center to center and a section diameter of $\frac{1}{8}$ of an inch. The diameter may be in excess of $\frac{1}{8}$ of an inch to put the rings under a slight compression at all times.

A round tubular handle 6 of about $\frac{1}{8}$ inch outer diameter and $\frac{3}{4}$ inch inner diameter having a length of about $7\frac{1}{2}$ inches is joined cross-wise at one end as by welding at 7 to barrel 1. A rubber sleeve or grip 8 tightly envelops the handle at its other end to remain secured thereon. Grip 8 is of oval section as shown in Figure 5 for the best hand grip and resilience, while the handle is shaped for improved shock absorption too, as compared to the opposite arrangement of an elliptic handle and round grip.

To assemble the parts of the head, the barrel and striker are first put into axial alignment with a pair of O-rings on each preset into the first and third grooves of each counting from the leading ends. Then the parts are pressed together under great force slowly while permitting the rings to roll progressively into their respective grooves.

As graphically represented in Figure 4, a hammer constructed with such restrained rolling rings (see curve A) was found to have less rebound than either a standard masonry hammer (see curve B) or the next best "no-bounce" hammer (see curve C), while at the same time tests showed that a greater proportion of the total impact energy (see curve X) was available for useful work with the hammer of this invention (see curve N) than with the other heretofore available "no-bounce" hammer (see curve O) as compared to the masonry hammer (see curve P). Thus, there is attained a high degree of shock isolation and energy transmittal. To the tool operator this means less hazard, inconvenience and fatigue. This may be attributed to the high coefficient of friction developed under compression, the hysteresis in the elastomer and to diversion of the forces to an angle athwart the axis of strike.

The invention in its preferred embodiment takes the form of a hand tool, but it will be understood that it has advantages when suitably designed in size for other types of hammers and rams to which operating force may be applied from a power source by any suitable mechanism so long as the steady pressing force, needed to disassemble the parts is not exceeded for the particular arrangement which may be varied to suit the operating load needed.

While in accordance with this invention one embodiment now believed preferred has been specifically illustrated and described, it should be understood that changes and modifications and equivalents thereof may occur to those skilled in the art and that therefore, the scope and spirit of this invention is not limited thereto or thereby except as set forth in the appended claims.

What is claimed is:

1. A tool for striking comprising an outer hollow open-ended member, an inner member carried in said outer member, one of said members including at an end thereof a striking head, and means connected to the other of said members for imparting thereto a striking force, said members having spaced juxtaposed surfaces each of which surfaces has a recess complementary to the recess in the surface of the other member, and a resilient elastic composition member restrained in said

complementary pair of recesses between said members and maintained therein for compression, said constrained resilient connection between said members permitting only limited relative movement of the members with respect to each other thereby substantially reducing the rebound of said tool and the shock imparted to said means without excessive loss of effective energy whenever said head is struck.

2. The hand-tool of claim 1 wherein the resilient member is a body shaped for rolling in said recesses and consists of a rubber-like material equivalent to rubber having a Durometer hardness of about 70.

3. A hand-tool for striking a body such as a pin, stud or the like comprising an outer hollow open-ended member, an inner solid member carried in said outer member, said inner member having at one end an enlarged striking head, and a handle connected at one extremity to the outer of said members and carrying a resilient hand-grip mounted at the other end, said members having spaced juxtaposed surfaces each of which surfaces

15 has a plurality of spaced circumferential grooves each complementary to the mating groove in the surface of the other member, and a resilient rubber-like composition ring member of a suitable Durometer hardness wedged in each of said complementary pair of grooves and maintained therein under confinement, said head being longitudinally spaced from the other member sufficiently with respect to said ring members forming a constrained resilient connection between said members

20 to permit limited longitudinal relative movement of said inner and outer members toward each other without interference of any one member with the other members, thereby substantially reducing the rebound of said tool and shock imparted to the hand of the tool operator

25 while transmitting a high proportion of the energy supplied, whenever said head is struck against said body in the direction of said movement the number of said rings being sufficient to effectuate said energy transmission longitudinally.

40 4. An impact device comprising an outer hollow barrel, an inner cylinder carried in the bore of said barrel, said cylinder including a striking end, said barrel and cylinder having spaced juxtaposed inner and outer surfaces, respectively, each of which surfaces has a circumferential groove complementary to the other of said grooves, and an elastomeric O-ring confined in said complementary pair of grooves for rolling under compression, said grooves having angularly sloped sides arranged tangentially to normally restrain said O-ring

45 in the middle of said groove while permitting only limited relative movement of said barrel and cylinder with respect to each other for diverting the reaction forces at an angle to the striking axis and dissipating the energy of restitution in elastic deformation and hys-

55 teresis.

5. The device of claim 4 wherein the sloping sides of the groove form an angle of about 120°.

6. The device of claim 4 wherein the O-ring is rubber having a Durometer hardness of about 70.

7. The device of claim 4 wherein the O-ring is of an enlarged diameter sufficient for placing the ring under compression between said grooves at all times.

8. A hammer comprising an open-ended barrel having sides of relatively elastic deformability, an inner rigid cylinder carried in the bore of said barrel and having a striking end, said barrel and cylinder having spaced juxtaposed inner and outer surfaces, respectively, each having about four circumferential grooves, the grooves of one being complementary to the grooves of the other and having straight sides intersecting at an angle of about 120°, a rubber O-ring of a Durometer hardness of about 70 disposed in each complementary pair of grooves, said angular sides being tangential to said ring, thereby putting the ring into rolling motion and simultaneous compression when said striking end is impacted.

9. The hammer of claim 3 wherein the handle is of circular cross section and the hand grip is of oval cross section, the major dimension of which is aligned in the direction of the striking axis of the cylinder.
